CLAIM

The ornamental design for a gaming machine, as shown and described.

DESCRIPTION

This design patent application also cross-references U.S. patent application Ser. No. 16/523,807, filed Jul. 26, 2019, all content of which is incorporated by reference in its entirety.

FIG. 1 is a front perspective view of a gaming machine showing our new design;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The dashed broken lines in the figures illustrate portions of the gaming machine that form no part of the claimed design.
